PROCESS AND APPARATUS FOR THE CONTINUOUS GASIFICATION OF SOLID FUELS

Willy Linder, Essen-Bredeney, Germany, assignor, by mesne assignments, to Koppers Company, Pittsburgh, Pa., a corporation of Delaware

Application June 30, 1937, Serial No. 151,112
In Germany July 4, 1936

2 Claims. (Cl. 48—203)

The invention relates to the continuous gasification of solid fuels of all kinds, especially coal, coke, brown coal or the like, by means of a preheated mixture consisting of air and steam for the purpose of producing combustible gases and more particularly to the gasification of fuel in an essentially vertical shaft through which the fuel passes from the top downwards and which is provided at the bottom with a grate suitable for the extraction of solid ash.

The gasification of solid fuels by means of a preheated mixture of steam and air is well-known per se. Such preheating is useful in that the quantity of steam that is to be delivered together with air into the gas generator for reaction with the fuel may be efficiently increased. The higher the quantity of steam that may be added, the greater will be the percentage of the more valuable water-gases that will be formed within the fuel bed. Further, by providing for passing much more steam into the bed, the slag will be cooled-down rapidly and granulated and the dangerous formation of big slag lumps will be avoided.

In the gas producers known hitherto, the shaft is provided at the bottom with a revolving grate by means of which the solid ash may be extracted from the shaft. This revolving grate is equipped with means for the removal of ash or slag in solid form from the gas producer shaft. The commonly used revolving grates are built with a cast-iron body, fitted with openings for the introduction of air-steam mixture into the fuel bed.

The temperature to which the steam-air mixture may be heated in a gas producer, provided with such a grate, depends on the heat resistance of the material used for the construction of the grate. This temperature lies about at 300-400° C. for the common forms of cast-iron revolving grates. If the temperature of the preheated steam-air mixture is higher, either the grate will be burnt out too quickly or prematurely, or it will be destroyed by stresses of heat expansion. It is impossible to construct the grate from a refractory material, because such material does not possess the necessary strength for the extraction and crushing of the ash lumps, which may be formed within the fuel bed.

There are also known further types of gas producers in which the preheated gasifying air is blown through nozzles, into the shaft wall of the gas producer. These gas producers are, however, operated in such a way, that the ash is extracted in liquid condition. As the liquefied ash can only

be drawn-off if the gas generator is operated at a definite minimum temperature, and as the operating temperature is decreased by introducing steam into the shaft, the quantity of the steam to be added to the gasifying air is thus limited and even with a comparatively high preheating of the gasifying air. Hence only a relatively small amount of steam can be introduced into a shaft of a liquid ash generator.

Now, the principal object of my present invention is to provide such improvements, which will make the operation of the gas producer independently of the unfavourable influences explained above, and which will make it possible to gasify the fuel by means of an air-steam mixture which contains more steam than one was able to add hitherto.

According to the present invention, the highly preheated steam-air mixture is introduced into the fuel column at a zone situated somewhat above the grate in the lower part of the shaft and simultaneously to introduce cold air or a suitable steam-air mixture into the fuel bed from below through the revolving grate, which serves as usual for the extraction of solid ash or slag, which cold air serves for burning the combustible residues still contained in the ash. When making use of the process according to my invention, the temperature of the preheated steam-air mixture may be so increased, that the ash in the fuel bed is prevented from becoming pasty or melted. The temperature of the steam-air mixture can, moreover, be increased far beyond that point, which is allowed in the operation of the usual revolving-grate gas producers, since the steam-air mixture is not introduced through the iron generator grate. Notwithstanding the comparatively high temperature of the fuel bed within the gasifying zone, the grate, on the other hand, is also kept cool by the cold air, introduced into the shaft through the grate.

The term "cold air" means within the scope of this invention, the gasifying media. These gasifying media may consist either of air only, or of air with a certain addition of steam, or moderately preheated air and/or steam. If necessary, it is also possible to increase the oxygen content of the gasifying air, or to introduce pure oxygen from below into the shaft and to avoid an increase of the temperature of the fuel bed in the neighborhood of the grate by an increased amount in the addition of steam to the colder air.

In order that this invention may be more readily understood and carried into practice, reference is hereby made to the accompanying draw-

ing showing in a vertical section the gas producer built according to the invention. The gas generator consists of the gasifier 1 and the liner 2, made of refractory brickwork. The upper part of 5 the gas producer is fitted with a fuel feeding arrangement 3 and an outlet for the useful gas. The gasifier shaft shows a slightly conical tapering in the lower part, which corresponds to the reduced quantity of fuel. The shaft is equipped 10 below with a revolving grate 5, which discharges the ash from the shaft into a trough 6. The revolving grate 5 is for instance, provided with an upper central hood 7, fitted with openings, said hood being connected with a pipe 8 for the supply 15 of the air-blast. The air main 10 controlled by a valve 9 is connected to the steam line 11 and to the pipe 8, regulated by a valve 12. Above the grate hood 7 of the revolving grate there is arranged in the gasifier wall quite a number of nozzle 20 openings 13, 14 and 15. These openings are formed by means of water-cooled nozzles 16, which are situated in a protection frame 17, so that they can be exchanged. Refractory lined pipeline branches 18, 19, 20 are connected with 25 the nozzles 16. The pipeline branches 18, 19 and 20 are coupled with a distributing pipe 21 and, if necessary, suitable regulating members may be inserted.

The distributing pipe 21 is supplied with the 30 steam-air mixture which has been brought to a high temperature in a suitable gas heater, which may, for example, comprise a set of regenerators, which are heated-up alternately, with a part of the generated useful gas.

35 The temperature of the steam-air mixture may be increased in the gas heater therefor, so that a considerable quantity of steam may be led into the gasifying shaft, together with the gasifying air, in order to be used there for reaction with 40 the fuel. This is of special importance for gasifying bituminous fuels, for example brown coal. During the gasification process of such fuels, a considerable quantity of waste liquors is produced in the cooling and purifying process for the useful 45 gases. The waste liquor is contaminated with organic acid constituents, such as phenol or other tarry matters. The quantity of the so-called low-temperature liquor is so high, that it could not be dealt with in the gas producers as heretofore known and operated. On the other hand, a different special treatment of the low-temperature liquor is often troublesome. This low-temperature liquor on account of its poisonous constituents, is not allowed to be discarded into the 50 natural water drainages, without a suitable pre-treatment. The invention now offers the possibility to destroy, by a very high heating of the steam-air mixture, producer, at the same time making a producer gas of a higher calorific value, since by 55 the now permissible preliminary very high heating of the steam-air mixture, the fuel bed can react with an amount of steam great enough to take up all such waste liquor if such waste liquor is employed as the source of aqueous medium for the steam for the highly heated air-steam mixture.

I have now described my present invention on the lines of a preferred embodiment thereof, but my invention is not limited in all its aspects to

the mode of carrying it out as described and shown, since the invention may be variously embodied within the scope of the following claims.

I claim:

1. A method of continuous gasification of solid 5 fuels by reaction thereof with a mixture of pre-heated air and steam comprising; maintaining a bed of continuously descending fuel; charging the fuel at the top of the bed and withdrawing the made gas continuously from the upper part of the 10 bed; subjecting the fuel in the lower part of the bed to continuous mechanical rotative agitation and ash crushing action and continuously discharging the ash thereof in solid form from the bottom of the bed; introducing a mixture of very 15 highly preheated air and steam into the fuel bed through the circumference thereof at a zone somewhat above the region of mechanical agitation and flowing the same upwardly through the bed for reaction therewith and withdrawal at the 20 upper part thereof; and concurrently with the introduction of the very highly preheated air and steam separately introducing steam and relatively cooler air into the lower portion of the bed through the mechanical agitation medium to cool 25 the same and diffusing the steam and relatively cooler air from the mechanical medium into the portion of the fuel bed between said mechanical medium and the region of entrance of the very highly preheated air and steam for combustion of 30 combustible residues of the ash and flowing the gas thereof upwardly through the fuel bed for off-flow therefrom together with the very highly preheated air and steam introduced to the fuel bed circumferentially thereof somewhat above 35 the mechanical medium.

2. A gas generator comprising a shell having a fuel bed gasification chamber, an upper fuel charging inlet and an upper gas outlet for said chamber; mechanical grate means in the base 40 of the chamber for diffusing gas into the fuel bed therein and rotatively crushing the ash thereof and continuously discharging the same from the fuel bed continuously at the base thereof; means for supplying a mixture of very highly 45 preheated air and steam to the fuel bed chamber, said means being connected with the circumference of the chamber through circumferential inlets somewhat above the level of the top of the mechanical grate means; and separate means for 50 supplying relatively cold air to the fuel bed concurrently with the operation of the means for supplying very highly heated air and steam, said mechanical grate means comprising elements for conveying and diffusing gas into the base of the 55 fuel bed, and said means for supplying relatively cold air communicating with said elements of the mechanical grate means to convey the relatively colder air thereto for cooling the grate means by the relatively cold air and discharge of 60 the colder air into the fuel bed for simultaneous flow upwardly through the same to the upper gas outlet together with the flow of very highly preheated air and steam from the circumferential inlets, and steam supply means connected 65 with the grate means for flow of steam along with the relatively cold air through the elements of the grate means.

WILLY LINDER.
